Primary Examiner — Robin V Webster(74) *Attorney, Agent, or Firm* — Mark C Jacobs(57) **CLAIM**

The ornamental design for a bag filler nozzle, as shown and described.

DESCRIPTION

FIG. 1 is a perspective view of the bag filler nozzle of this design with a front tip and an end connector.

FIG. 2 is a top plan view thereof.

FIG. 3 is a right side elevational view thereof. The left side is a mirror image thereof.

FIG. 4 is a bottom plan view thereof.

FIG. 5 is a front elevational view thereof.

FIG. 6 is a rear elevational view thereof.

FIG. 7 is a perspective view of the bag filler nozzle of this design with a same front tip and a second rear end connector.

FIG. 8 is a top plan view thereof.

FIG. 9 is a right side elevational view thereof. The left side is a mirror image thereof.

FIG. 10 is a bottom plan view thereof.

FIG. 11 is a front elevational view thereof; and,

FIG. 12 is a rear elevational view thereof.
